WITNESS

Patented Aug. 26, 1924.

UNITED STATES PATENT OFFICE.

OLE O. KOLSTAD, OF DULUTH, MINNESOTA.

MAIL BOX.

Application filed June 30, 1922. Serial No. 372,801.

To all whom it may concern:

Be it known that I, OLE O. KOLSTAD, a citizen of the United States, residing at Duluth, in the county of St. Louis and State of Minnesota, have invented new and useful improvements in Mail Boxes, of which the following is a specification.

This invention relates to deposit and collection receptacles, particularly to mail boxes, and has for its object the provision of a mail box designed to be built into the wall of a house or other building and constructed in the nature of an elongated box like casing provided at its upper end with an entrance door located at the outside of the building and provided at its lower end with an outlet door for permitting the removal of mail matter disposed within the device.

20 An important object is the provision of a device of this character which is capable of adjustment so that it may be built into a thin or thick wall with equal satisfaction, the structure being furthermore such that a very 25 neat appearance will be assured.

Another object is the provision of a device of this character which is formed of sections which are detachably engaged and which may be adjusted for varying the length of 20 the device, the lower section being furthermore capable of being arranged so that the outlet door will be disposed at the opposite side of the wall from the inlet door or at the same side if such should be found preferable for any reason as for instance in building the devices into the entrance halls of apartment houses and the like.

A still further object is the provision of a pivoted plate within the entrance end of the 40 device whereby to prevent removal of any mail matter from the entrance end while not interfering with the placing of mail therein.

An additional object is the provision of a 45 device of this character which will be simple and inexpensive in manufacture and installation, efficient and durable in service and a general improvement in the art.

With the above and other objects and ad- 50 vantages in view, the invention consists in the details of construction to be hereinafter more fully described and claimed, and illustrated in the accompanying drawings, in 55 which:

Figure 1 is a longitudinal section through my device showing it built into a wall,

Figure 2 is a cross sectional view, Figure 3 is an elevation of the entrance end of the device,

Figure 4 is an elevation of the outlet end 60 of the device,

Figure 5 is a vertical section showing the device arranged to have both doors at the same side of the wall, and

Figure 6 is a face view of the wall with 65 the parts arranged as in Figure 5.

Referring more particularly to the drawings the letter A designates the wall of a building which if of frame construction would naturally be hollow, the space being 70 capable of receiving my device to be described. In the event that the device is used in a wall of brick formation or the like it is apparent that a cavity would have to be left during the building or else chiseled out 75 afterwards. This however has no bearing on the present invention, but is mentioned as illustrating how my device might be installed.

In carrying out my invention I provide an 80 elongated receptacle which consists of an upper section 10 telescopically engaged within a lower section 11, both sections being preferably rectangular in cross section and the lower section being formed with a 85 lateral extension 12 and having one lower corner rounded as shown at 13, with the bottom inclined as shown at 14. The upper section 10 is formed substantially as an elbow and is designed to project through an 90 opening B in the wall A the opening being at the outside of the wall. Slidably engaged upon this projecting end is a flanged member 15 which constitutes a face plate for presenting a neat appearance. The lower end 95 of the lower section 11 is also of elbow like formation and extends through an opening C in the inner face of the wall, a flanged member 16 being engaged upon the projecting end for providing the necessary face 100 plate. It is to be noted that the sections 10 and 11 are telescopically engaged so that they may be slid toward or from each other to vary the length of the casing defined by 105 them.

The flanged members 15 and 16 are similar in construction and each includes a sleeve 15° adapted for insertion within the section 10 or 11 as the case may be. The material from which the sleeve is formed is bent upon 110 itself as shown at 15° to define a pocket 15° receiving the end of the section 10 or 11

snugly. The metal is rebent upon itself as indicated at 15^a to define an outer sleeve 15^a which fits within the opening in the wall, this outer sleeve terminating in a flange 15^b which bears against the face of the wall for providing a neat finish. The provision of these members 15 and 16 is important as they are adjustably telescopically engaged upon the right angularly extending ends of the sections 10 and 11 so as to fit walls of different thicknesses.

Hinged upon the lower edge of the projecting end of the lower section 11 is a door 17 which swings downwardly when opened 15 to form a continuation of the inclined bottom 14 so as to constitute a chute which will facilitate the discharge of mail. This door is of course provided with any suitable lock 18 and handle 19.

20 The projecting end of the upper section 10 is provided with a hinged door 20 which swings upwardly when opened and which is so arranged as to exclude rain and draft. This door is of course provided with any 25 suitable handle 21 by means of which it may be opened by the mail carrier.

Pivoted at 22 within the angle of the upper section 10 is a compound curved plate 23 which is for the purpose of preventing 30 the removal of mail through the upper end of the device in an obvious manner while not interfering in any way with the depositing of mail matter in the device.

In installing this structure in apartment 35 houses and the like, that is in the entrance halls or lobbies thereof, it is desirable that the inlet and outlet doors be in the same side of the wall. In Figures 5 and 6 I have shown the device arranged in this way. In 40 these figures it will be obvious that the section 11 is associated with the section 10 in the reverse manner to that shown in Figure 1 so that the projecting ends of both sections will be at the same side of the wall. Owing 45 to the fact that the sections are merely telescopically slidably engaged it is apparent that there is no difficulty in varying the arrangement.

From the foregoing description and a 50 study of the drawings it is apparent that I have thus provided a simply constructed mail box which is adjustable to meet various conditions, especially variations in the widths or thicknesses of walls into which it 55 is built. The various advantages to be derived from the use of the structure will be

apparent from an inspection of the drawings when considered with the above explanation so that further elaboration is deemed unnecessary.

60 While I have shown and described the prefered embodiment of the invention, it is of course to be understood that I reserve the right to make such changes in the form, construction and arrangement of parts as 65 will not depart from the spirit of the invention, or the scope of the subjoined claims.

Having thus described my invention I claim:

70 1. A mail box adapted to be built into a wall and comprising a pair of vertically arranged sections disposed in telescoping engagement whereby to be extensible or contractable, each section being substantially L-shaped whereby to provide a right angular extension adapted for location within an opening in the wall, and a face plate formed from a single sheet of metal bent upon itself to define a double ply flange engaged 75 telescopically upon the right angular extensions and fitting within the wall opening, the face plate being further formed with a sleeve portion projecting outwardly beyond the face of the wall, the sleeve portion being spaced inwardly of the double ply flange 80 to define a socket space receiving the free end of the right angular extension, said sleeve portion being telescoped within the 85 right angular extension.

90 2. A mail box comprising an elongated receptacle adapted to be built into the wall of a building, said receptacle being formed of slidably connected sections, the upper section being provided at its upper end with a right 95 angular extending end portion extending through an opening in the wall and being provided with a door, and the lower end of the lower section being formed with a right angular extension extending through an 100 opening in the wall of the building and provided with a door, and a plate pivoted within the angle of the upper section for preventing extraction of mail through the door of the upper member, said plate being pivoted nearer its rear edge than its forward edge whereby the forward edge will normally overbalance the rear and lie upon the bottom of the right angular extensions of the uppermost section.

105 In testimony whereof I affix my signature.
OLE O. KOLSTAD.
